UNITED STATES PATENT OFFICE.

ANTONIO PARRELLA, OF WASHINGTON, DISTRICT OF COLUMBIA.

SIGNAL.

1,287,412.

Specification of Letters Patent. Patented Dec. 10, 1918.

Application filed February 20, 1918. Serial No. 218,266.

To all whom it may concern:

Be it known that I, ANTONIO PARRELLA, a citizen of the United States, residing at Washington, in the District of Columbia, have invented certain new and useful Improvements in Signals, of which the following is a specification.

This invention relates to signals and more particularly to a signal adapted for use upon motor vehicles to indicate to the driver of a following vehicle that the car upon which the signal is mounted is about to make a turn.

It is the object of the invention to provide a signal of the character above set forth that will be simple in construction, certain in operation and one which will display a very distinctive and well recognized signal indicating danger, that will be visible from the rear of the machine upon which it is located.

Further objects and advantages of the invention will be set forth in the detailed description which now follows.

In the accompanying drawing:

25 Figure 1 is a longitudinal vertical section of a signal constructed in accordance with the invention and with the parts in the position they occupy when the signal is displayed.

30 Fig. 2 is a like view with the parts in the position they occupy when the signal is not displayed and

35 Fig. 3 is a vertical section upon line 3—3 of Fig. 1 looking in the direction indicated by the arrow.

Like numerals designate corresponding parts in all of the figures of the drawing.

Referring to the drawing 5 designates a cylindrical casing one end of which is flared 40 as indicated at 6 and the other end of which carries a bracket 7 by which the cylinder 5 may be secured to the windshield or other convenient part of a motor vehicle with the cylinder 5 projecting at right angles to the line of travel thereof and beyond the side thereof.

The rear end of the cylinder 5 has an opening 8 formed therein for the passage of a stem 9, the inner end of which carries an 50 operating handle 10. A stop collar 11 is disposed upon the stem 9 outwardly of the cylinder and limits the movement of the stem into the cylinder. The stem 9 is pivoted at 12 to a link 13 and this link is 55 pierced at 14 for the passage of a strip of spring metal 15. The opposite ends of the

strip 15 are bent upon themselves as indicated at 16 and between the portions 15 and 16 is engaged a band of red fabric 18. The link 13 carries a collar 19 and a spring 20 60 bears between this collar and the rear end of the cylinder 5.

Under normal conditions the parts lie in the position illustrated in Fig. 2, at which time the stem 9 lies at right angles to the cylinder 5 and the spring 20 is compressed. At this time the spring 15 and the red fabric band 18 are collapsed and drawn into the cylinder 5 where they are out of sight. When it is desired to display the signal the 70 handle 10 is grasped and the stem 9 is brought into alignment with the link 13, the handle is then released and the spring 20 acts to move the parts to the position illustrated in Fig. 1. As the spring strip moves 75 out of the mouth of the tube it expands and brings the red fabric band to the fan formation illustrated in Fig. 1 thus forming a signal of fan shape and of a distinctive color that will be visible for a considerable distance to the rear.

It is to be noted that by virtue of the novel arrangement of the parts wherein the strip 15 is bent upon itself at 16, the band 18 is efficiently held while at the same time 85 a metal surface is provided which acts upon the flaring mouth of the tube when the signal is to be moved to the position illustrated in Fig. 2, and which strip is collapsed and thereby collapses the fabric portion of the 90 signal without the fabric portion of the signal coming into contact with the tube or cylinder 5.

The structure herein shown and described is a simple and inexpensive one that may be 95 manufactured at a small cost but will be entirely efficient for the purpose for which it is intended.

It is to be understood that the invention is not limited to the precise construction set 100 forth but that it includes within its purview whatever changes fairly come within the spirit of the appended claim.

Having described my invention what I 105 claim is:

A device of the character described, comprising a relatively stationary tubular casing having one end open and its opposite end provided with a head having a contracted opening, a signal device adapted for 110 longitudinal movement within the stationary tubular casing and to automatically

open upon being moved to the exterior of the same, a link operating within the tubular casing and connected with the signal device, a spring surrounding the link and tending to move the link and the signal device toward the open end of the tubular casing, and a stem adapted to operate within the contracted opening in said head and having pivotal connection with the link and

having a portion thereof projecting forwardly beyond the pivotal connection to serve as a lock when the stem is arranged rearwardly of the contracted opening and swung upon its pivot to assume a position at substantially a right angle to the link. 10 15

In testimony whereof I have affixed my signature.

ANTONIO PARRELLA.
